COMBINED BOTTLE HOLDER AND CAP

George J. Collinet, Chicago, Ill.

Application June 6, 1955, Serial No. 36,368

Term of patent 14 years

(Cl. D58—26)

Fig.2

Fig. 1 is a perspective view of a combined bottle holder and cap embodying my new design; and

Fig. 2 is a top plan view of the same.

The dominant feature of my design resides in the portions shown in full lines.

I claim:

The ornamental design for a combined bottle holder and cap, as shown and described.
